SAFETY RAZOR

William Fielden Vaughan, Knoxville, Tenn.

Application April 3, 1935, Serial No. 14,502

1 Claim. (Cl. 30—41)

This invention relates to safety razors, an important object of the invention being to provide a safety razor including a blade having four cutting edges, the construction of the razor being such that when in operation, two cutting edges are exposed, the remaining cutting edges being guarded.

Another important object of the invention is to provide a razor of this character so constructed that the handle will be substantially waterproof eliminating any possibility of water entering the handle to cause rust or corrosion.

A further object of the invention is the provision of a safety razor which may be thoroughly cleaned and adjusted without the necessity of dismantling the razor.

Still another object of the invention is to provide yieldable means for gripping and cushioning the blade, whereby the blade may be adjusted so that the user may shave close by merely tightening the handle. A still further object of the invention is to provide means for holding the blade against rotary movement on the shank of the razor, when the sections of the razor have been operated to facilitate cleaning of the razor.

In the drawing:

Figure 1 is a longitudinal sectional view through a safety razor constructed in accordance with the invention.

Figure 2 is a sectional view through the razor in its extended position for cleaning.

Figure 3 is an elevational view of the body portion of the razor.

Figure 4 is a sectional view taken on line 4—4 of Figure 2.

Figure 5 is a sectional view illustrating the means for securing the rubber cover to the guard member of the razor.

Figure 6 is a fragmental sectional view illustrating a modified form of rubber securing means.

Referring to the drawing in detail, the reference character 5 designates the shank or stem of the razor, the shank or stem being provided with threads 6 disposed at the outer end thereof, whereby the shank or stem may be secured to the body portion 7 of the razor, the threaded end being positioned in a threaded opening of the body portion.

Formed on the shank or stem 5, and arranged in spaced relation with the outer end of the shank, are ribs 8 which are spaced apart and disposed longitudinally of the shank. An annular flange indicated by the reference character 9 is formed integral with the shank or stem 5 at the inner ends of the ribs 8, providing a support for

the razor blade 10, when the sections of the razor are loosened and separated to facilitate cleaning of the razor. Thus it will be seen that due to this construction, it is unnecessary to dismantle the razor for cleaning purposes.

The handle of the razor is indicated by the reference character 11 and as shown, the handle is hollow and formed with an opening through which the reduced end 12 of the shank extends, the reduced portion 12 being headed so that the handle is secured to the shank or stem 5.

Positioned within the handle and surrounding the shank or stem 5 of the razor, is a tubular member 13 that has a guard plate 14 formed at the inner end thereof, the guard plate being provided with the usual guard edges 15.

As clearly shown by the drawing, the inner surface of the body portion or plate 7 is covered by the strip of rubber material 16, which is positioned by moulding the rubber to closely fit the inner surface of the body portion 7.

The surface of the guard member 14, adjacent to the plate 10, is also provided with a rubber cover 18, which is also held in position on the guard plate 14, by means of the clips 19, which are embedded in the rubber material, and pass through openings in the guard plate, where they are bent over to engage the guard plate. It will of course be understood that the strip of rubber material which is reinforced by metallic strip 17 may be secured to the member 7 by means of screws 19' which pass through the rubber material and strips 17 and are fitted in threaded openings of the member 7 as shown at Figure 6.

External threads 20 are formed on the tubular member 13 and are adapted to cooperate with the internal threads formed on the sleeve 21, whereby the tubular member 13 may be secured in its active position, when the razor is adjusted for use.

One end of the sleeve 21 is reduced as at 22 and fits within a recess formed in the inner end of the handle 11.

As clearly shown by Figure 1 of the drawing, the tubular member 13 is formed with an inner tapered shoulder 23 adapted to receive the annular flange 9 formed on the shank or stem 5 of the razor preventing the shank or stem 5 from sliding through the tubular member 13, when the razor is adjusted for replacing the razor blade.

It will of course be understood that the razor blade, which is shown more particularly by Figure 4 of the drawing, is formed with openings 24, which openings receive the studs 25 extending from the guard plate 14, whereby the blade is

held against rotary movement with respect to the guard plate 14. In order that the blade may be properly positioned, the openings 24 are numbered, and it will be seen that due to this construction, the user of the razor may know at all times, the edges which have been used in shaving, and the edges which have not been used thus facilitating the positioning of the blade with respect to the guard plate.

10 The blade is also formed with a central opening through which the shank or stem extends, the central opening of the blade being formed with notches 26 that accommodate the ribs 8, preventing rotary movement of the blade with respect to the shank or stem 5, when the body portion 7 and guard plate 14 have been moved to facilitate the cleaning of the razor, without the necessity of dismantling the razor, to accomplish the cleaning result.

15 20 It might be further stated that because of the rubber members 16 and 18, the blade 10 is securely gripped, and by merely rotating the sleeve 21, pressure on the blade 10 may be increased or decreased, to the end that the blade may be

regulated so that the user may get various types of shaves, and at the same time the rubber members will protect the various elements of the razor from moisture insuring against the formation of rust or corrosion.

Having thus described the invention, what is claimed is:

A safety razor comprising a shank, an enlargement on the shank, a body portion secured to one end of the shank, a tubular member positioned on the shank and having a shoulder with which the enlargement engages restricting movement of the shank through the tubular member, a guard plate on one end of the tubular member, spaced longitudinal ribs on the shank, a blade 15 having a central opening through which the shank extends, said blade having notches adjacent to the central opening and adapted to accommodate the ribs preventing rotary movement of the blade with respect to the shank, and means for moving 20 the guard plate into clamping relation with the body portion clamping the blade therebetween.

WILLIAM FIELDEN VAUGHAN.
